DESIGN FOR A STOVE

Application filed November 14, 1930. Serial No. 37,660. Term of patent 14 years.

To all whom it may concern:

Be it known that we, (1) LEE S. CHADWICK, (2) MARC RESEK and (3) CHARLES J. KESSLER, citizens of the United States, residing at (1) Shaker Heights Village, (2) Cleveland Heights, and (3) Cleveland Heights, in the county of Cuyahoga, and State of Ohio, have invented a new, original, and ornamental Design for Stove, of which the following is a specification, reference being had to the accompanying drawing, forming part here-

of, wherein the figure is a perspective view of a stove showing our new design. The opposite sides of the stove are identical with each other in appearance.

We claim:

The ornamental design for a stove as shown and described.

LEE S. CHADWICK.
MARC RESEK.
CHARLES J. KESSLER.
